UNITED STATES PATENT OFFICE.

JOHN M. MARTY, OF CLEVELAND, OHIO.

VENTILATING APPARATUS.

1,170,551.

Specification of Letters Patent.

Patented Feb. 8, 1916.

Application filed November 5, 1914. Serial No. 870,392.

To all whom it may concern:

Be it known that I, JOHN M. MARTY, a citizen of the United States, residing at Cleveland, in the county of Cuyahoga and State of Ohio, have invented certain new and useful Improvements in Ventilating Apparatus, of which the following is a specification.

My invention relates to improvements in ventilating or air distributing apparatus, the present embodiment being particularly designed and adapted for use between the ceiling and floor walk of halls, rooms, and the like, in maintaining a substantially uniform temperature throughout by providing for a constant circulation of air between the upper and lower portions thereof, thereby preventing the accumulation of relatively warm and cold non-circulating zones of air thereby also reducing the number of heat units required to establish and maintain the required temperature.

A further object is to provide an exceedingly simple, cheap, and efficient apparatus of this class which may be readily adapted to the varying demands of actual service, as well as one which may be readily and cheaply installed in buildings of the varying and conventional designs now in use, and which, when so installed, will not impair the beauty of the architecture or in any way interfere with the original purposes and uses of such building.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification, Figure 1, is a side elevation of a ventilating apparatus constructed and installed in accordance with this invention, the upper and lower portions being shown in central vertical section for the purpose of clearer illustration of the parts. Fig. 2, an enlarged cross sectional view taken on line 2-2 of Fig. 1; Fig. 3, a central vertical sectional view of a modification in which the air conduit is in the form of a hollow column or pillar and the fan

and motor are arranged within the base portion thereof.

Similar numerals of reference designate like parts throughout all the figures of the drawings.

The improved ventilating or air distributing apparatus comprises a vertically arranged air conduit adapted to be disposed between the horizontally extending walls to be heated, or in other words, between the ceiling 1, and the floor or base wall 2. The upper end of the air conduit is provided with air induction ports 3, and the lower end of the air conduit is provided with air eduction ports 4, the primary object being to take in the warm air from the ceiling 1, through the induction ports 3, and to discharge it through the eduction ports 4, the constant suction or downward flow of the air being produced through the medium of a fan 5, mounted in the lower portion of the conduit and above the air eduction ports 4. It is apparent also that the ports 3 and 4, may be extended through suitable pipe conduits to any part of the room desired. The fan 5, is mounted on a fan shaft 6, and is adapted to be driven by a motor 7, or any other suitable and convenient device.

The vertically arranged air conduit is preferably detachably connected to and interposed between a flanged ceiling plate or ring 8, and a base or floor plate 9, the latter being also adapted to support the motor 7. In the form or embodiment of the invention shown in Fig. 1 the motor 7, is arranged outside of the air conduit and is adapted to drive the fan through the medium of a belt 7^a, and a pulley 7^b.

As a means of filtering the air through the eduction ports 4, the latter are preferably provided with beveled or outwardly flaring edges 4^a, adapted to removably receive and contain correspondingly beveled filtering plates or frames 10, carrying a filtering element or medium 10^a, and as a means of removably retaining said filtering frames 10, in position as well as providing means for opening and closing or partially opening and closing the eduction ports 4, and thereby regulating the suction exerted through the conduit by the fan 5, a circum-

ferentially movable ring valve 11, is provided, said ring valve being arranged outside of the base portion of the air conduit and above the base or floor plate 9, and being 5 provided with openings 11^a, adapted to be brought into and out of registry with the air eduction ports 4.

In the form or embodiment shown in Figs. 1 and 2 of the drawings the air conduit consists of a vertically arranged ceiling pipe 12, and a second vertically arranged pipe 13, adjustably connected to the pipe 12, through the medium of a clamping ring 14, the lower end of the pipe 13, being connected 15 to a fan housing 15, mounted upon a conduit base section 16, the latter being provided with the air eduction ports 4, constructed and arranged as hereinbefore described.

20 In the form or embodiment shown in Fig. 3, the air conduit is in the form of a hollow column or pillar 17, and the fan 5, and motor 7, are arranged within the base portion thereof so as to be concealed from view 25 as well as to disguise the entire apparatus in the form of an ordinary column or pillar.

From the foregoing description, taken in connection with the accompanying drawings, the operation and advantages of my invention will be readily understood.

Having thus described some of the embodiments of my invention, what I claim and desire to secure by Letters Patent, is,—

1. In a ventilating apparatus, the combination with a ceiling and a floor, and a vertically arranged air conduit pipe having air inlet ports near said ceiling; of a fan and fan housing mounted on said floor connected to the lower end of said air conduit pipe, said fan housing being provided with air 35 eduction ports, and means for opening and closing said air eduction ports whereby to regulate the suction exerted by said fan.

2. In a ventilating apparatus, the combination with a ceiling and a floor, and a vertically arranged air conduit having air inlet ports near said ceiling and air eduction ports near said floor; of a suction device within said air conduit above said air eduction ports, and means for regulating or 45 opening and closing said air eduction ports whereby to regulate the suction exerted by said suction device.

In testimony whereof I have affixed my signature in presence of two witnesses.

JOHN M. MARTY.
